Primary Examiner — John Windmuller*Assistant Examiner* — Steven Czyz(74) *Attorney, Agent, or Firm* — Lora J. Graentzdoerffer(57) **CLAIM**

The ornamental design for a soap dispenser, as shown and described.

DESCRIPTION

FIG. 1 is a perspective view of a soap dispenser showing my design;

FIG. 2 is a front elevation view;

FIG. 3 is a rear elevation view;

FIG. 4 is a left side elevation view; wherein the right side elevation view is a mirror image thereof;

FIG. 5 is a top plan view; and,

FIG. 6 is a bottom plan view.

The broken lines indicate portions of the soap dispenser that form no part of the claimed design.
